APPARATUS FOR SEMIAUTOMATICALLY
OPERATING A LAUNDRY MACHINE

Lawrence Joseph Gernon, Brooklyn, N. Y.

Application November 12, 1929
Serial No. 406,625

12 Claims. (CL. 68—9)

This invention relates to a control for laundry machines and more particularly to a semi-automatic electrical control system for a flat-work ironer which decreases the possibility of mixing pieces from one bundle into another bundle as the bundles are passed through said flat-work ironers.

It has long been recognized that the successful operation of a commercial laundry is directly dependent upon the ability to pass the work of one customer through the laundry with dispatch and without commingling said work with that of another customer. Furthermore, any confusion or commingling can be directly traced to the introduction of the human element in handling the work.

The primary object of this invention is the provision of a control for the laundry machines used in a commercial laundry which will decrease the reliance upon the human equation.

Another object of the invention is the provision of a semi-automatic electrical control system for a flat-work ironer.

Another object of the invention is the provision of a control for a flat-work ironer, whereby the operators of the same are less liable to make mistakes and cause mix-ups in the work being handled.

Another object of the invention is the provision of a control for a flat-work ironer which is automatically shut down upon the passage of the work of one customer therethrough and which is manually remotely started by the operator on the take-off side of the ironer, who is at the strategic point for supervising said manual starting.

Other and further objects of the invention will be obvious to one skilled in the laundry art, as the description of said control system is hereinafter developed.

According to the present invention, the motor of the flat-work ironer is started by the closure of a normally open switch adjacent to the take-off board by the take-off operator. Said normally open switch closes a control circuit which energizes a magnet to close the motor switch having a front contact which maintains said control circuit and said magnet in energized condition through a pair of brush contacts. A clutch is provided having one disc thereof actuated by a rotating shaft of the ironer and the slidable element thereof resiliently held in a definite position during disengagement, and adapted upon engagement to interrupt the aforementioned control circuit after a pre-determined rotation. The

slidable element of said clutch is placed in engaging position by means of a fork member attracted by a second magnet connected in a second circuit having a normally closed switch which is automatically operated by the feeding operator and which is also maintained by a front contact in energized condition after opening of said switch.

The invention will be more clearly understood by referring to the accompanying drawings in which similar reference numerals designate similar elements and wherein:

Figure 1 is a diagrammatic view of the electrical circuits and a vertical longitudinal cross-section of the magnetically operated friction clutch.

Figure 2 is a section on the line II—II of Figure 1.

Figure 3 is a section on the line III—III of Figure 1.

Figure 4 is an end view of the friction clutch of Figure 1.

The motor 10 which actuates the flat-work ironer is connected through a motor switch 11 and main switch 12 to the supply mains 13, 14, 15 and 16. Mains 13 and 14 are the legs of one phase and mains 15 and 16 are the legs of a second phase. A four-pole single throw main switch 12 has the poles thereof connected to fuses 17, 18, 19 and 20, and allows manual interruption of the motor circuit. Wires 21 and 22 connect fuses 19 and 20, respectively, to the motor 10.

The motor switch 11 comprises two sets of main contacts 23 and 24, 25 and 26, of a known type as used on circuit breakers. Main contact 23 is connected to fuse 17, while main contact 24 is connected through a terminal post 28 and wire 27 to the motor 10. Also, main contact 25 is connected to fuse 18, while main contact 26 is connected through a wire 29 to the motor 10.

Closing of the main switch 12 and the motor switch 11 thus completes one phase to the motor through supply main 13, the first pole of switch 12, fuse 17, main contacts 23 and 24, terminal post 28, wire 27, motor 10, wire 21, fuse 19 and the third pole of main switch 12, to supply main 14. The second phase is completed through supply main 15, the second pole of main switch 12, fuse 18, main contacts 25 and 26, wire 29, motor 10, wire 22, fuse 20 and the fourth pole of the main switch 12, to supply main 16.

The motor circuit has been illustrated as a two phase system because it is deemed that from such a disclosure it is more evident how this invention can be adapted to single phase, three phase, or direct current motor circuits. The

present disclosure is applicable without change to a three phase four wire with grounded neutral motor circuit, the grounded neutral being connected to supply main 16. For a three phase, 5 three wire motor circuit, supply main 16 and the respective wire will be eliminated. For single phase and direct current adaptation, supply mains 13 and 14 are used, except that fuse 19 is connected to the motor 10 through main contacts 25 and 26 and wire 29, instead of through wire 21.

Main contacts 24 and 26 are both mounted on a pivotal arm, not shown, but of a known type such as is generally used in magnetic switches 15 or circuit breakers, and which is actuated by an electro-magnet 30. One side of the electro-magnet 30 is connected to a terminal post 31 and by a wire 32 to the fuse 19. An insulated strip 39 receives two threaded arms 35 and 40 which are 20 attached thereto by means of nuts 34 and 38, respectively. Said arm 35 contains a coil spring 37 engaging a brush contact 36 while arm 40 contains a coil spring 42 engaging a brush contact 41. A wire 33 leading from one side of electro-magnet 25 30 is connected to arm 35 under one of the nuts 34. A split annular ring 43 of conducting material 30 engages brush contacts 36 and 41, which are resiliently pressed by coil springs 37 and 42, respectively, against said ring 43 to make good contact therewith. Said brush contacts 36 and 41 35 may be made of any material adapted to make good sliding contact and of a comparatively low resistance, such as carbon or compounds thereof.

A normally open switch 45 having two terminal posts 46 and 47 is biased to open position by a coil spring 45' holding a switch member 45' in raised position and is positioned on the flat-work ironer adjacent to the take-off board where it can be readily closed by the operator when said 40 take-off board has been cleared of the work of one customer. This switch may also be placed so that it is easily accessible to any operator who is in a supervisory position. A wire 44 connects upper nut 38 and arm 40 of brush contact 41 45 to terminal post 46 of the normally open switch 45 and terminal post 47 of said switch 45 is connected to fuse 17 by means of a wire 48. Thus when switch 45 is closed a starting control circuit 50 is completed across supply mains 13 and 14 through the third pole of switch 12, fuse 19, wire 32, terminal post 31, electro-magnet 30, wire 33, upper nut 34, arm 35, brush contact 36, ring 43, brush contact 41, arm 40, upper nut 38, wire 44, switch 45, wire 48, fuse 17 and the first pole 55 of main switch 12. Consequently, closure of switch 45 causes electro-magnet 30 to be energized which in turn causes the sets of contacts 23 and 24, 25 and 26, to make contact with each other, thereby closing the motor circuit and 60 starting the flat-work ironer.

A front contact 49 is also mounted on the aforementioned pivotal arm with main contacts 24 and 26, and is adapted to make contact with a contact post 50 when the electro-magnet 30 is energized. The contact post 50 is connected by means of a wire 51 to terminal post 46 of the normally open switch 45 and the front contact 49 is connected to the main contact 24, so that after 65 main contacts 23 and 24 make contact and switch 45 is again in open position, the circuit through electro-magnet 30 is then completed through wire 51, contact post 50, front contact 49, main contacts 23 and 24, fuse 17, and the first pole of main switch 12 to supply main 13.

70 The shaft 52 of the flat-work ironer has a

spindle 53 mounted thereon. The shaft 52 may be a shaft for one of the steam cylinders of the cylinder type flat-work ironer. It may be a shaft for one of the rolls of the chest type flat-work ironer, or may be any other shaft which is suitable and convenient. A pinion gear 54 is mounted on said spindle 53 by means of a washer 55 and a nut 56, which is threaded on said spindle 53.

80 A frame 57 is provided with a hole 58 receiving clutch shaft 59. A washer 60 encircles said clutch shaft 59 and abuts the frame 57, while a nut 61 is threaded on said shaft 59 in abutting relation to said washer 60. A collar 62 is integral with shaft 59 adjacent frame 57 on the side 85 opposite said washer 60 and said nut 61. A second pinion gear 63 is rotatably mounted on said clutch shaft 59 and engages the pinion 90 54 on the shaft 52 of the ironer. A collar 64 having a set screw 65 is mounted on clutch shaft 59 adjacent pinion gear 63, so that the same may be rotated without axial movement upon shaft 59, which is held stationary on the frame 57 as previously described. The gear ratio between pinion gears 54 and 63 will depend 95 upon the speed of rotation of the shaft 52 and upon the type of flat-work ironer which is being used. The gear ratio should be such that the pinion gear 63 will make slightly less than one revolution during the time that it takes a piece 100 of work to pass through the flat-work ironer. In practice with a commercial type of flat-work ironer, it was found for a certain speed of the motor 10 that it took about 53 seconds for the work to pass through the ironer, and that at the 105 same motor speed the shaft 52 was making one revolution in twenty seconds. The use of a three to one gear ratio between pinion gears 63 and 54, therefore, results in said pinion gear 63 making fifty-three sixtieths (53/60) of a revolution 110 during the time that one piece of work is passing through the ironer. It will be obvious that this fractional rotation of the pinion gear 63 will not be affected by a change in the speed of the motor 10.

115 An annular ring 66 of material having a high friction coefficient, such as fibre, is concentrically mounted on the pinion gear 63. A disc 67 having a ring 68 concentric and integral therewith, is slidably mounted upon the clutch 120 shaft 59, ring 68 having the same inner and outer diameters as ring 66. The split annular ring 43 is inlaid in the periphery of disc 67, and except for the space 69, (see Figure 2), completely encircles the same. The disc 67 and ring 125 68, which is integral therewith, are made of an insulating material having a high friction coefficient, which is preferably the same as that used for ring 66, so that there will be the greatest friction effect possible between rings 66 and 130 68 when they make contact with each other.

135 A metal ring 70 is also slidably placed upon clutch shaft 59 and is attached to disc 67 by means of a plurality of screws 71 having the heads thereof countersunk in disc 67. A groove 72 is provided in the periphery of metal ring 70. A pair of circular plates 73 and 74 are placed upon clutch shaft 59 and held in spaced relation by a plurality of sleeves 75 and screws 76. Circular plate 73 is attached to metal ring 70 140 by means of a plurality of screws 77 having the heads thereof countersunk in the circular plate 73.

145 A spiral spring 78 is mounted in the space between the circular plates 73 and 74, the inner 150

end of said spring 78 being attached to shaft 59 by a pin 79 (see Figure 3), and the outer end thereof forms a loop about one of the sleeves 75.

Sufficient clearance is provided between the edges of the spiral spring 78 and the plates 73 and 74, so that when the plates are displaced axially during engagement of the clutch they will not strike the edges of the spring 78.

A stop collar 80 is positioned on the clutch shaft 59 by means of a set screw 81 and acts as a stop for the disengaging axial movement of the slideable element of the clutch, which is caused by a helical spring 82 which abuts pinion gear 63 and disc 67, to normally hold rings 66 and 68 in spaced relation. Spring 82 is centered about the shaft 59 by means of aforementioned collar 64. A rod 83 is threaded into stop collar 80 and projects radially therefrom, to act as a stop for a pin 84 positioned on the plate 74. A lock nut 83' is threaded on rod 83 to hold the same in a set position.

A bracket 85 is mounted on the frame 57 and an insulating plate 86 is mounted in turn upon said bracket 85. A contact post 87 with a contact point 88 is mounted on said plate 86 by means of nuts 89 threaded on said post 87. An electro-magnet 90 is mounted on said plate 86 and is connected by the wires 91 and 92 to the terminal posts 93 and 94, respectively, which are also mounted on said insulating plate 86.

A forked arm 95 is pivotally mounted at 96, so that the fork fits into the groove 72 in metal ring 70, and said forked arm 95 is in magnetic relation to electro-magnet 90, so that the latter on being energized attracts the forked arm 95 which in turn causes the slideable clutch members 67, 70, 73 and 74, to move, so that ring 68 is in frictional engagement with ring 66. The split annular ring 43 is of such a width that brush contacts 36 and 41 engage the same even after axial displacement of the disc 67. Upon frictional engagement of the rings 66 and 68, the disc 67 is rotated in the direction of the arrow in Figure 2, against the action of the spiral spring 78 until brush contacts 36 and 41 are on the insulating space 69.

When electro-magnet 90 is de-energized, helical spring 82 moves the slideable elements 67, 70, 73 and 74 of the clutch axially, so that plate 74 strikes stop collar 80 and spiral spring 78 turns elements 67, 70, 73 and 74 on clutch shaft in a direction opposite to that shown by the arrow in Figure 2, until pin 84 abuts rod 83. The slideable elements are then in the same position as before electro-magnet 90 was energized.

A front contact 97 is mounted upon an insulated portion 98 of the forked arm 95, and is so positioned that it makes contact with contact point 88, when the electro-magnet 90 is energized and attracts said forked arm 95. Front contact 97 is connected by a wire 99 to a terminal post 100, which is mounted upon insulating plate 86.

A wire 101 connects contact post 87 to terminal post 93 which is in turn connected by a wire 102 to the terminal 104 of a normally closed switch 103. The other terminal 105 of said normally closed switch 103 is connected to the terminal post 28 of the motor switch 11 by means of a wire 106. A wire 107 is connected between terminal post 28 and terminal post 100. A wire 108 extends between terminal post 94 of the insulating plate 86 and the terminal post 31 of the motor switch 11.

The switch member 113 of the normally closed

switch 103 is biased to closed position by a coil spring 113'. In such biased or closed position switch 103 will place the electro-magnet 90 across supply mains 13 and 14, through the first pole of main switch 12, fuse 17, main contacts 23 and 24, terminal post 28, wire 106, switch 103, wire 102, wire 91, electro-magnet 90, wire 92, wire 108, terminal post 31, wire 32, fuse 19, and the third pole of main switch 12 to supply main 14. After the electro-magnet 90 has attracted the forked arm 95, the contact point 88 will make with front contact 97, and the normally closed switch 103 will be shunted by the wire 107, terminal post 100, wire 99, front contact 97, contact point 88, contact post 87 and wire 101, so that the electro-magnet will continue to be energized after switch 103 is again opened.

An incandescent lamp 109 is connected across terminal posts 93 and 94 by means of wires 110 and 111. Said lamp 109 is located near the take-off board.

A wooden pole 112 has one end thereof resting upon the switch member 113 of the normally closed switch 103, to hold the same in open position against the action of coil spring 113'. This pole is used on the feeding side of the flat-work ironer and holds the flat work of one customer in a convenient position in front of the flat-work ironer while the work is being fed into said ironer. When the pole 112 is in this position, it maintains switch 103 open, and when all the flat work of one customer, which was on the pole, has been fed into the ironer, the pole is removed to make way for a similar pole with another customer's flat work bundle thereon. As the pole 112 is removed, the switch 103 is automatically closed.

The operation of the semi-automatic electrical control is as follows:

Assuming the main switch 12 and the motor switch 11 are closed, the motor 10 is operating and the shaft 52 is rotating pinion gears 54 and 63. Meanwhile, the clutch is in the disengaged position and the switch 103 is being held open by the pole 112. After all the flat work on the pole has been fed into the ironer, said pole 112 is removed, switch 103 normally closes, electro-magnet 90 is energized and lamp 109 is lighted. This lighting of lamp 109 warns the take-off operator that the last piece of one bundle has been fed into the machine, and that the first piece of the next bundle will soon follow. Fork 95 is now attracted by electro-magnet 90 and front contact 97 makes with contact point 88 of contact post 87 to shunt switch 103. Thus the feeding operator may place another pole 112 in position, in order to feed another customer's flat work into the ironer, thereby opening switch 103 without de-energizing electro-magnet 90.

The attraction of forked arm 95 also brings rings 66 and 68 into frictional engagement, so that clutch disc 67 is rotated against the action of spiral spring 78. By the correct selection of a gear ratio between gears 63 and 54 and by moving collar 80 either clockwise or counter-clockwise on shaft 59, the mechanism may be so set that space 69 of disc 67 will come under the brush contacts 36 and 41, just as the last piece of the customer's bundle is being discharged onto the take-off board.

When the brush contacts 36 and 41 reach the space 69, the circuit of the electro-magnet 90 across supply mains 13 and 14 will be interrupted, main contacts 23 and 24, 25 and 26 will be separated and the motor 10 will be shut down, since

- both phases have been interrupted. It should be noted that the time interval between engagement of the clutch and the shutting down of the motor is directly proportional to the speed of the shaft 52, so that the speed of the motor 10 may be varied and still the motor circuit will be interrupted, just as the last piece of work is being discharged onto the take-off board.
- Said interruption of the motor circuit and main contacts 23 and 24 will de-energize the electro-magnet 90 and break the circuit to the lamp 109. The helical spring 82 will act to disengage the clutch and move fork member 95 away from contact point 88 and electro-magnet 90. Spiral spring 78 will rotate disc 67 in a direction opposite to the arrow in Figure 2 until pin 84 abuts rod 83 and brush contacts 36 and 41 are again connected through the split annular ring 43 of conducting material.
- If the take-off operator has not been able to clear the take-off board of all the pieces of one bundle, this shutting down of the ironer will now present an opportunity to do so before any pieces of the next bundle are discharged onto the board.
- This feature of the control system is of the utmost importance, for if the take-off board is not clear and the work of another customer is discharged onto said board, the possibility of confusion and a mix-up is greatly increased. It is the general practice to feed the large pieces of any one bundle, such as sheets and table cloths, into the ironer last and these should be attended to immediately upon being discharged onto the take-off board. Consequently, any small pieces, such as napkins, towels, pillow cases, etc., not yet folded when the first large piece is discharged onto the take-off board, are placed to one side until the large pieces are folded. Now if the ironer were not shut down, the small pieces of the next customer's work would be on the take-off board at the same time as the unfolded small work of the previous customer, and commingling is most likely to occur under such circumstances.
- Furthermore, observation has disclosed that once the take-off operators get behind in their folding they can only catch up, if at all, a bit at a time, so that this simultaneous occurrence of two customers' work on the take-off board will happen several times before the operators have made up the lost time.
- When the take-off board is clear, the operator presses the switch member 45' of the normally open switch 45 and closes the circuit through the electro-magnet 30 across the supply mains 13 and 14. Main contacts 23 and 24, 25 and 26 will make and the motor 10 will start. Front contact 49 will make with contact post 50 and shunt the switch 45 so that the motor switch will remain closed even after normal opening of the switch 45. Shaft 52 is now rotating pinion gears 54 and 63 and the cycle will be repeated upon removal of the wooden pole 112.
- The control system has been described with respect to that type of flat-work ironer operation which utilizes wooden poles placed before the ironer. However, it is within the scope of this invention to place a switch at any position on the feeding side of the ironer so that it will be automatically or manually closed after the last piece of flat work of one customer's bundle has been fed into the ironer.
- Since many different and varied modifications of this invention are conceivable, the above disclosure and the accompanying drawings are to

be construed in an illustrative and not in a limiting sense.

Having now described my invention, what I claim is:

- An apparatus for operating a laundry machine, comprising a starting control circuit, a running circuit having a portion in common with said starting control circuit, a stopping control means normally inoperative but adapted after a predetermined operating cycle to interrupt the common portion of said circuits, a mechanical means adapted to operate said stopping control means, and a magnetic means adapted to be energized and to move said mechanical means into operative position whereby said predetermined cycle starts upon energization of said magnetic means for operation of said mechanical means. 80
- In a device of the character described, the combination with a starting control circuit, a running circuit having a portion in common with said starting control circuit, a stopping control means normally inoperative but adapted after a predetermined operating cycle to interrupt the common portion of said circuits, a mechanical means normally inoperative but adapted to operate said stopping control means, a clutch means normally disengaged but adapted upon engagement to actuate said mechanical means, and a magnetic means adapted to move said clutch means into engagement, of a resilient means 85 90 95 adapted to return said mechanical means to a definite position after disengagement of said clutch means. 100
- In a device of the character described, the combination with a starting control circuit, a running circuit having a portion in common with said starting control circuit, a stopping control means normally inoperative but adapted after a predetermined operating cycle to interrupt the common portion of said circuits, a mechanical means normally inoperative but adapted to operate said stopping control means, a clutch means normally disengaged but adapted upon engagement to actuate said mechanical means, and a magnetic means adapted to move said clutch means into engagement, of a resilient means 105 110 115 120 125 means adapted to rotate said mechanical means in a reverse direction after disengagement of said clutch means, and an adjustable stop means adapted to stop the reverse rotation of said mechanical means in a definite position. 130
- An apparatus for semi-automatically operating the motor switch of a motor operated laundry machine, comprising a normally open starting control circuit containing an electro-magnetic means actuating said motor switch and a normally open switch means, a holding circuit shunting said starting control circuit after the motor switch is closed, a stopping control means normally inoperative but adapted after a predetermined operating cycle to interrupt said starting control and holding circuits, a mechanical means normally inoperative but adapted to operate said stopping control means and to start the predetermined operating cycle thereof, a clutch means normally disengaged but adapted upon engagement to operate said mechanical means, an electro-magnetic circuit having an electro-magnet and causing said clutch means to engage when said electro-magnet is energized, and a switch means in said electro-magnetic circuit adapted to close the same and to energize said electro-magnet. 135 140 145 150
- An apparatus for semi-automatically operating the motor switch of a motor operated laun-

- dry machine, comprising a normally open starting control circuit containing an electro-magnetic means actuating said motor switch and a normally open switch means, a holding circuit shunting said starting control circuit after the motor switch is closed, a stopping control means normally inoperative but adapted after a predetermined operating cycle to interrupt said starting control and holding circuits, a mechanical means 10 normally inoperative but adapted to operate said stopping control means and to start the predetermined operating cycle, a clutch means normally disengaged but adapted upon engagement to actuate said mechanical means, an electro-magnetic circuit having an electro-magnet and causing said clutch means to engage when said electro-magnet is energized, a switch means in said electro-magnetic circuit adapted to close the same and to energize said electro-magnet, and a 15 holding circuit adapted to shunt said switch means after said electro-magnet is energized, said electro-magnetic circuit being opened when said stopping control means have operated.
6. An apparatus for semi-automatically operating the motor switch of a motor operated laundry machine, comprising a normally open starting control circuit containing an electro-magnet adapted to close said motor switch and a normally open switch which upon being closed causes said 20 motor switch to close and laundry machine to operate, a holding circuit shunting said starting control circuit once said motor switch is closed, a front contact on said motor switch completing said holding circuit, a friction clutch having a 25 driving disc and a driven disc, said driving disc being actuated by said laundry machine, mechanical means actuated by the driven disc of said friction clutch, stopping control means actuated by said mechanical means and adapted to interrupt said starting control and holding circuits, a second electro-magnetic circuit having an electro-magnet which upon being energized causes said friction clutch to engage, a switch in said second electro-magnetic circuit which upon 30 being closed causes said electro-magnet to be energized, a second holding circuit containing a second front contact shunting said switch, said second front contact being open when said second electro-magnet is de-energized.
- 50 7. An apparatus for semi-automatically operating the motor switch of a motor operated laundry machine, comprising a normally open starting control circuit, a holding circuit shunting said starting control circuit after said motor switch is closed, a friction clutch comprising a rotating ring actuated by said laundry machine and a disc adapted to engage said ring and rotate therewith, a split annular ring mounted on the periphery of said disc, a pair of brush contacts abutting said 55 annular ring and completing said starting control and holding circuits therethrough, said disc being rotated to bring the split of said ring beneath said brush contacts, a spiral spring rotating said disc in reverse direction upon disengagement of said clutch, and adjustable stop means positioned to stop said reverse rotation of said disc in a definite position with the split annular ring electrically connecting the two brush contacts, a forked arm means actuating said disc 60 axially, a clutch control circuit for said friction clutch completed through a switch and containing an electro-magnet magnetically actuating said forked arm means, and a second holding circuit adapted to shunt said switch and maintain said friction clutch control circuit until the 65 split of said annular ring comes beneath said brush contacts.
8. An apparatus for semi-automatically operating the motor switch of a motor operated flat work ironer, comprising a normally open starting control circuit, a holding circuit shunting said starting control circuit after said motor switch closes, a stationary shaft mounted on said ironer, a friction clutch comprising a ring rotatably mounted to rotate on said shaft and actuated by said flat work ironer, and a disc slidably and rotatably mounted on said shaft, a split annular ring mounted on the periphery of said disc, brush contacts resiliently abutting said split annular ring and completing said starting control and holding circuits therethrough, said split annular ring being so set as to bring the split portion beneath the brush contacts after a predetermined rotation of said disc thereby interrupting electrical connection between the brush contacts and opening said starting control and holding circuits, a metal ring provided with a peripheral groove and attached to said disc, a pair of plates rotatably mounted on said shaft in spaced relation and attached to said metal ring, a spiral spring mounted between said plates having the outer end thereof attached to said plates and the inner end thereof attached to said shaft, a collar adjustably mounted on said shaft having a rod projecting radially therefrom, and a pin mounted on one of said plates adapted to abut said rod when said friction clutch is rotated by said spiral spring, a forked arm pivotally mounted and engaging said peripheral groove of said metal ring, a clutch control circuit for said friction clutch 90 energizing an electro-magnet which attracts said pivotally mounted forked arm, a switch in said clutch control circuit, and a second holding circuit comprising a contact means closed to shunt said switch when said electro-magnet is energized.
9. In an apparatus for semi-automatically operating a laundry machine, the combination with a starting control means, a stopping control means adapted after a predetermined operating cycle 95 to stop said machine and a controlling means adapted to operate said stopping control means, of a second controlling means for controlling said first mentioned controlling means and a means normally maintaining said second controlling means in effective position but adapted to be retained in ineffective position by a laundry holder.
10. In an apparatus for semi-automatically operating a laundry machine, the combination with a starting control circuit a running circuit completed by said starting control circuit, a stopping control means normally inoperative but adapted after a predetermined operating cycle 100 to interrupt said running circuit, a mechanical means adapted to operate said stopping control means and a magnetic means adapted upon being energized to move said mechanical means into operative position, of a controlling means for controlling said magnetic means and a means 105 normally maintaining said controlling means in effective position but adapted to be retained in ineffective position by a laundry holder.
11. In an apparatus for semi-automatically operating a laundry machine, the combination with a starting control means, a stopping control means normally inoperative but adapted after a predetermined operating cycle to stop said machine, a mechanical means normally inoperative 110 but adapted to operate said stopping control 115

means whereby said operating cycle is started, a clutch means normally disengaged but adapted upon engagement to actuate said mechanical means, and a magnetic means normally de-energized but adapted upon being energized to move said clutch means into engagement, of a controlling means for controlling said magnetic means and a means normally maintaining said controlling means in effective position but adapted to be retained in ineffective position by a laundry holder.

12. In an apparatus for semi-automatically operating a laundry machine, the combination with a starting control means, a stopping control means normally inoperative but adapted after

a predetermined operating cycle to stop said machine, a mechanical means normally inoperative but adapted to operate said stopping control means whereby said operating cycle is started, a clutch means normally disengaged but adapted upon engagement to actuate said mechanical means, and a magnetic means normally de-energized but adapted upon being energized to move said clutch means into engagement, of a controlling circuit for controlling said magnetic means and a switch means normally completing said controlling circuit but adapted to be maintained in open position by a laundry holder.
